UNITED STATES PATENT OFFICE.

CHARLES H. BROWN, OF SYRACUSE, NEW YORK.

CAR-STARTER.

SPECIFICATION forming part of Letters Patent No. 390,443, dated October 2, 1888.

Application filed April 6, 1888. Serial No. 269,782. (No model.)

To all whom it may concern:

Be it known that I, CHARLES H. BROWN, of Syracuse, county of Onondaga, in the State of New York, a citizen of the United States, have 5 invented certain new and useful Improvements in Car-Starters, of which the following is a specification, reference being had to the accompanying drawings, in which—

Figure 1 is an elevation from one side with 10 one of the main wheels removed. Fig. 2 is a front elevation. Fig. 3 shows details of the grip-block, a top plan, and a vertical section on line α . Fig. 4 is a horizontal section on line $\gamma\gamma$ in Fig. 1. Fig. 5 is a sectional elevation of 15 the grip-block and driving pulley, with the grip-block and lever engaged with the pulley.

My invention relates to devices designed to aid the starting of street-railway cars and other vehicles.

20 My object is to produce such a device of simple construction and of great utility.

It consists in the several novel features of construction and operation hereinafter described, and specifically set forth in the claims 25 hereunto annexed.

It is constructed as follows: A is the car, mounted upon the axle 1, upon which are the wheels 2, in any ordinary manner. Upon this axle, between the wheels 2, I secure the double-flanged pulley 3. Upon the bottom of the car, in suitable slides, 4, I place the draft-rod 5, upon the front end of which is a hook, 6, and adjacent thereto is a ratchet, 7; and 8 is a pawl 30 engaging with the ratchet, the pawl being

35 mounted in the dash of the car-platform, and to the rear end of this rod is secured a rope or chain, 9, passing over the pulley 10 and secured to the lever 11. This lever is pivotally mounted in the grip-block 12, said block being slotted 40 longitudinally, as shown in Fig. 3 at 13, a slotway converging from the front and rear ends of the grip to the hole which receives the pin upon which the lever is mounted. In the front edge of this grip is a gripping-slot, 14, 45 curved to correspond with the curve of the periphery of the wheel 3, the arms 15 of the slotway hooking over the flanges of the wheel 3. The point of the lever 11 is beveled, as shown in Fig. 5. I also show a lever pivotally mounted 50 in the platform of the car and having its lower

end pivotally connected to the draw-bar 5, so that by this lever 16 the draw-bar can be moved back and forth in the slides.

It is operated as follows: In Fig. 1 I show the car at a standstill. Then, when strain or 55 draft is applied to the draw-bar 5, it is drawn outward, pulling the chain with it, which first raises the rear end of the lever, and this throws the lever-point firmly against the periphery of the pulley 3, and, secondly, the continued 60 strain upon the lever draws the grip-block against the flange of the wheel, and all together cause the pulley 3 to rotate, carrying with it the axle and the main wheels 2, rotating them, and thus starting the car. 65

It will be observed that when strain is applied to the draw-bar the first effect is to throw the point of the lever against the periphery of the pulley-wheel 3, the point bearing firmly against it, and that the second effect is that as 70 the strain continues the leverage of the lever upon the grip-block, its point having then a fulcrum bearing upon the pulley, draws the grip tightly against the inner face of the double flange, and that on account of the hinge-connection between the lever and grip-block the grip block is free to oscillate, so that it will conform itself to the inner face of the flanges, thus giving the block a bearing for its whole length against the flange, thereby giving a 75 stronger grip and reducing the chances of slipping to the minimum.

What I claim as my invention, and desire to secure by Letters Patent, is—

1. The combination, with the axle and double-flanged wheel mounted thereon between the main supporting-wheels of the car, of a grip-block inclosing both flanges of the wheel, and a lever hinged to the grip-block and connected to the draft-bar, substantially as described. 85

2. The combination, with the pulley 3, provided with a double flange, of a grip-block slotted vertically to embrace the flanges and adapted to be raised vertically against them by the strain upon the lever 11, hinged to the 90 grip-block, and provided with a point adapted to have a fulcrum bearing against the pulley, substantially as described. 95

3. The combination, with the pulley 3, of the grip-block 12, slotted vertically to receive the 100

flanges of the pulley, and the lever 11, provided with a beveled point and connected to the draft-bar 5, substantially as described.

4. The combination of a lever, 11, engaging 5 with the periphery of the pulley 3, and the grip-block 12, hinged to the lever and receiving the flanges of the pulley in a vertical slot, and bearing against the inner surfaces of the

pulley-flanges when power is applied to the lever, substantially as described. to

In witness whereof I have hereunto set my hand this 4th day of April, 1888.

CHAS. H. BROWN.

In presence of—

C. W. SMITH,

H. P. DENISON.
